UNITED STATES PATENT OFFICE.

WILLIAM FREDRICKS AND AUGUSTUS BROWN, OF NEW YORK, N. Y.

TOY REVOLVER.

SPECIFICATION forming part of Letters Patent No. 278,005, dated May 22, 1883.

Application filed March 21, 1883. (No model.)

To all whom it may concern:

Be it known that we, WILLIAM FREDRICKS and AUGUSTUS BROWN, of the city, county, and State of New York, have invented 5 certain new and useful Improvements in Pneumatic Toy Revolvers, of which the following is a specification.

This invention has reference to an improved pneumatic revolver that is to be used by children and others for throwing darts and other missiles; and the invention consists of the combination, with a supporting-frame having a main barrel at its front end and a rear extension-barrel in line therewith, of a flexible tube 10 attached to the extension-barrel and provided with a mouth-piece, and of a revolving cylinder having a number of chambers and mechanism whereby the chamber is rotated and one barrel after another thrown axially in line 15 with the fixed main barrel and the extension-barrel, so as to throw the darts placed in the chambers of the cylinders.

In the accompanying drawings, Figure 1 represents a side elevation of our improved pneumatic revolver. Figs. 2 and 3 are detail vertical transverse sections of the same, respectively on lines *x x* and *y y*, Fig. 1.

Similar letters of reference indicate corresponding parts.

Our pneumatic revolver consists of a supporting-frame, A, of metal or other suitable material, which is provided with a handle, A', cast integral therewith.

To the front part of the frame A is attached 35 the main barrel B, and to the rear part a shorter extension-barrel, B', in line with the barrel B. To the extension-barrel B' is applied a flexible tube, C, having a mouth-piece, C'. The frame A is further provided with revolving cylinder D, having a number of chambers, D', which turn on a spindle, D², passed through a center sleeve of the cylinder and secured to frame A. A trigger, E, serves to revolve the cylinder D by means of a slide-piece, E', which is pivoted to the trigger E and guided along frame A.

The slide-piece E' is provided with an inwardly-bent dog, e, that engages a ratchet-wheel, e', on the center sleeve of the revolving cylinder D when the trigger is pulled back,

so as to turn thereby the cylinder for a part of its revolution.

A spring, e², is interposed between the handle A' and the trigger E, and serves to return the latter into normal position, together with 55 the slide-piece E', ready for the next pull of the trigger and rotary motion of the cylinder D.

The barrels D' of the revolving cylinder D are supported by a center disk, D³, that has as many notches at the circumference as there 60 are barrels D', said notches d being engaged by a spring-pawl, d', whenever one of the barrels D' has been set into line with the main and extension barrels B B' by the action of the trigger E and slide-piece E'. The barrels 65 of the revolving cylinder D are charged with darts or other suitable missiles, and one barrel after the other brought by the revolving mechanism into line with the fixed barrels B B'. The darts are then thrown by blowing through 70 the flexible tube C and barrels B' B.

The fitting of the individual barrels D' of the revolving cylinder D to the barrels B B' is obtained by means of rubber sleeves e³, that are applied to both ends of the barrels D', said 75 sleeves projecting slightly beyond the edges of the barrels, so as to form contact with the ends of the barrels B B'.

When the cylinder is charged, as many darts or other missiles as there are barrels may be 80 successively hurled at a target, and thus a neat and entertaining revolver furnished for the use of children and grown people.

Having thus described our invention, we claim as new and desire to secure by Letters 85 Patent—

1. The combination of a frame, A, having a fixed front barrel, B, and a rear extension-barrel, B', in line therewith, a flexible tube, C, applied to the extension-barrel and having mouth-piece C', a revolving cylinder, D, having barrels D', and means, substantially as described, whereby the cylinder is revolved and one barrel after another is thrown into line with the fixed barrels B B', substantially as set forth. 95

2. The combination of frame A, having handle A', main barrel B, rear extension-barrel, B', flexible tube C, having mouth-piece C', revolving cylinder D, having barrels D', spring-pressed trigger E, pivoted slide-piece E', hav- 100

ing dog *e*, engaging a ratchet, *e'*, secured to the center sleeve of the revolving cylinder *D*, and means for locking the revolving cylinder to the frame *A* whenever a barrel has been set into line with the main and extension barrels *B B'*, substantially as and for the purpose set forth.

In testimony that we claim the foregoing as

our invention we have signed our names in presence of two subscribing witnesses.

WILLIAM FREDRICKS.
AUGUSTUS BROWN.
